MEANS FOR CONTROLLING WELLS

James L. Minahan, San Antonio, Tex.

Application May 26, 1934, Serial No. 727,644

4 Claims. (Cl. 166—15)

This invention relates to new and useful improvements in means for controlling wells.

One object of the invention is to provide an improved well controlling device which may be installed as a blowout preventer, said device being constructed of non-abrasive material and having a weight substantially or nearly equal to the total working pressure in pounds of the well flow to be controlled.

Another object of the invention is to provide an improved well controlling device which is arranged to be placed over the well-hole, and which is constructed of non-abrasive material, said device providing a control head system, thereby eliminating the usual abrasive Christmas tree connections, etc.

An important object of the invention is to provide an improved means for positively controlling an oil or gas well which is running wild.

A further object of the invention is to provide improved means for extinguishing the flame of a wild-burning well, and at the same time control production, whereby a minimum loss of the well fluid is sustained.

An important object of the invention is to provide a well controlling device, the weight of which is substantially or nearly equal to the total working pressure in pounds of the well flow to be controlled, whereby when said device is placed over the well, the pressure of said well flow is insufficient to displace the same.

Still another object of the invention is to provide an improved well controlling device having a passage therethrough, said device being arranged to be placed over an oil or gas well, the passage registering with the well-hole, said device having means for positively cutting off the flow of oil or gas through the passage therein.

An important object of the invention is to provide an improved method of controlling wells which consists, in placing an apparatus over the well-hole, said apparatus having a weight substantially or nearly equal to the total working pressure in pounds of the well, and also having a passage therethrough, and then controlling the flow of fluid through said passage.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is an elevation of a well controller

constructed in accordance with the invention and positioned over a well,

Figure 2 is an enlarged view of the controller, partly in elevation and partly in section,

Figure 3 is a plan view of the same,

Figure 4 is a view, partly in elevation and partly in section and taken at right angles to Figure 2,

Figure 5 is a longitudinal, vertical, sectional view of the control plate mounting,

Figure 6 is a horizontal, cross-sectional view of the same, taken on line 6—6 of Figure 5, 10

Figure 7 is a transverse, vertical sectional view, taken on line 7—7 of Figure 5,

Figure 8 is a detail of the control plate shaft mounting,

Figure 9 is a vertical sectional view of another form of the invention, and,

Figure 10 is an isometric view of another form of control plate.

In the drawings, the numeral 10 designates a body which is an inverted frustum of a cone, the enlarged base forming the upper side of the body. The body may be constructed of any material suitable for the purpose but is preferably made of concrete. By making the body of concrete, 20 said body is not only heat resisting and fireproof but is also non-abrasive. A central vertical passage or bore 11 extends through the body and when the body is positioned over a well, as will hereinafter be explained, said bore registers with 30 the well-bore. The upper end of the bore has an internally screw-threaded collar 11' molded into its upper end and the lower end of the bore is flared at 12 as shown in Figure 2.

The body 10 is constructed particularly for the well on which it is to be used and the weight of said body is an important feature of the invention. The weight of the body is substantially or nearly equal to the total working pressure in pounds of the well on which the body is to be placed. It is essential that the body be this heavy, at least, but it is possible to make the same heavier if desired. Thus, when the body is placed over the well, (Figure 1) the pressure of said well is insufficient to move the same. As has been explained, the bore 11 registers with the well hole and in the case of an oil well running wild, the oil will shoot upwardly through the bore.

For effectively closing the bore and preventing 50 escape of oil therethrough after the body is in position over the hole, a pair of control plates 13 are provided. The plates are positioned one on each side of the bore at approximately midheight of the body and are mounted to slide horizon-

tally across said bore. The mounting of each control plate is identical and a description of one will suffice. Each plate is mounted to slide horizontally within a casement 14 (Figures 5, 6, and 7). The casement is rectangular in cross-section and is molded within the concrete body being reinforced and braced therein by reinforcing bolts 15.

The casement is considerably longer than the plate and a worm screw 16 is mounted to travel forwardly from right to left, (Figures 5 and 6) within the casement. The forward end of the screw is rigidly mounted in the rear of the plate so that lateral movement of the screw will move the plate forwardly and backwardly in a horizontal plane, (Figure 5).

For imparting movement to the screw, an enlarged gear 17 is mounted in the casement behind the plate 13. The gear 17 is in constant engagement with a pinion 18 mounted on the lower end of a vertical shaft 19 which extends through the upper end of the body. The shaft is rotatable within a suitable casing 20 and the pinion is housed within an upwardly extending section 12' of the casement 12. The upper end of the shaft extends through a suitable bearing box 21 and a handle 22 has connection with the shaft through a universal joint 23. It is obvious that the operator can readily rotate the shaft 19 which in turn, will move the worm screw 16 through the medium of the gears 17 and 18, and move the control plate. The screw is held against rotation by a lug 16' depending from said screw and engaging in a guide slot which extends laterally beneath said screw. Drain pipes 24 connected with the bottom of the casement carry off excess lubricating oil or dirt which may accumulate in said casement.

When the worm screw is moved the plate 13 is moved inwardly within the bore 11 of the body. Since the plates are opposite each other, each plate moves inwardly so as to cover one half of the bore, whereby when both plates are at their extreme inward position, the bore is closed off. It is clear when the plates are within the bore, they will become covered with oil, dirt and the like. For cleaning the plates as they are retracted from the bore, a cleaner 25 is provided for each plate. The cleaner is mounted at the inner end of the casement and may be combined with a packer 26 whereby leakage of lubricating oil from the casement or leakage of gas or oil from well hole are prevented.

The cleaner and packer casing may be made integral with the inner end of the casement 14, as shown, and said cleaner and packer extend completely around the control plate (Figure 7). As the plate is retracted, it will be wiped free of any dirt or accumulation by said cleaner.

In using the device described for controlling an oil well which is running wild, the body 10 is constructed as described, the weight of said body being substantially equal to the total working pressure in pounds of the well. The body is then lowered over the well, by a hoist or other means (not shown). Suitable handles 21 are molded in the top of the body for this purpose. The control plates are retracted at this time, and the bore is open. The bore is registered with the well hole and the oil or gas rushes upwardly through said bore. It is desirable to decrease the pressure of the fluid to some extent to permit easier operation of the control plates to close the bore. For this purpose, the body is provided with a pair of inclined vertical passages 29 which

have check valves 30 mounted therein. Water and mud, or other material may be pumped downwardly through the passages, and serves to diminish the pressure to a certain extent.

The control plates are then slid to close the bore and the oil or gas coming out of the well will strike the plates and fall downwardly, thereby cutting off its escape. Since the weight of the body is greater than the pressure of the well, the body cannot be dislodged and will effectively control the well. With the well under control the control plates may be retracted and a casing head or other apparatus (not shown) screwed into the collar 11' at the upper end of the bore and the oil taken from the well in the usual way. The device may also be used on the usual well as a blowout preventer or control head system. When used as such, the body 10 is lowered over the well and the oil is withdrawn from the well through the bore 11 of said body. If the device is used as a blowout preventer a pair of control plates 13' (Fig. 10) are substituted for the plates 13. Each plate 13' has a semicircular cut-out portion 14' which engages around the drill stem (not shown) which passes downwardly through the body. It is pointed out that the cut-out 14' may be made of any desired size depending on the size of the pipe passing downwardly into the well hole.

If an uncontrolled well is on fire, the device is used similarly to when the well is running wild, the body being lowered into the crater caused by the fire (Fig. 1), and it is clear that the concrete being fireproof will not be affected. Further, concrete is non-abrasive and the oil, and sand carried therewith, rushing upwardly within the bore 11 will not affect the walls of the same.

In Figure 9, I have shown another form of the invention. The construction is the same except that the bore is provided with an expansion chamber 31 above the control plates. A cut-off valve 31' is mounted in the collar at the top of the bore. As the oil rushes upwardly, with the control plates retracted, said oil strikes the chamber. The sudden expansion reduces the pressure and the oil then escapes through horizontal outlet pipes 32 extending to the outside of the body 10. In this form a flared nipple 33 is provided at the bottom of the bore to permit the body to be attached to the upper end of the well casing. Although, throughout the description, I have described the device as used on an oil well, it is obvious that the body 10 will effectively control gas, mineral, and other wells and the invention is not to be limited to oil wells.

The description which has been given recites more or less detail of a particular embodiment of the invention, which is set forth as new and useful; however, I desire it understood that the invention is not limited to such exact details of construction, because it is manifest that changes and modifications may be made, within the scope of the appended claims, without departing from the spirit of the invention.

What I claim and desire to secure by Letters Patent is:

1. A well flow controlling device comprising, a body having sufficient weight to hold it in place at the top of the well against the flowing pressure thereof and having a central vertical passage therethrough for the well fluid, and means in the body for closing off said passage, the body having additional passages for conducting a fluid through said body into the well for diminishing the pressure of the well fluid.

2. A well flow controlling device comprising, a nonabrasive body having sufficient weight to hold it in place at the top of the well against the flowing pressure of said well and having a vertical passage therethrough, and slideable control plates in the body for closing said passage, the body having additional passages for conducting a fluid through the body into the well for diminishing the pressure of the well.
- 5 3. A well flow controlling device comprising, a body having sufficient weight to hold it in place at the top of the well against the flowing pressure thereof and having a passage therethrough for the well fluid, slideable control plates in the body 10 for closing off said passage, and means for slid-
- 15 ing said control plates, the body having additional passages for conducting a fluid through the body into the well for diminishing the pressure of said well.
4. A well flow controlling device comprising, a body having sufficient weight to hold it in place at the top of the well against the flowing pressure thereof and having a passage therethrough for the well fluid, slideable control plates in the body 5 for closing off said passage, a traveling worm screw connected to each control plate, gears connected with said worm screw and means at the top of the body for operating said gears to slide the plates.
